UNITED STATES PATENT OFFICE.

DWIGHT G. McCARTY, OF EMMETSBURG, IOWA.

SORTING TABLE OR FILE-DISTRIBUTING DEVICE.

Application filed June 8, 1920. Serial No. 387,449.

To all whom it may concern:

Be it known that I, DWIGHT G. McCARTY, a citizen of the United States, and resident of Emmetsburg, in the county of Palo Alto and State of Iowa, have invented a certain new and useful Sorting Table or File-Distributing Device, of which the following is a specification.

The object of my invention is to provide a device of simple and inexpensive construction, for distributing correspondence for convenience and economy of time in filing.

With this and other objects in view, my invention consists in the construction, arrangement and combination of the various parts of my device, whereby the objects contemplated are attained, as hereinafter more fully set forth, pointed out in my claim and illustrated in the accompanying drawings, in which:

Figure 1 shows a front elevation of a correspondence distributing device embodying my invention.

Figure 2 shows a perspective view of a receiving cabinet or box forming part of my invention.

Figure 3 shows a front elevation of the correspondence separating sheets; and

Figure 4 shows a side elevation of the device shown in Figure 3.

In the accompanying drawings I have used the reference numeral 10 to indicate generally a supporting stand or table. The table 10 preferably has the two drop leaves 11 and 12, at opposite sides, which leaves may be raised when the device is being used, for furnishing space upon which letters and papers may be laid out for convenience in handling.

Resting on the table 10 is a case 13, which has the form of a box or the like, of greater length than width, which box is provided with a vertical partition 14 running from end to end, and preferably with a transverse partition 15 extending from front to rear and located nearer one end than the other.

These partitions divide the box into four compartments, A, B, C and D. The compartments A and B are longer than the compartments C and D, and the compartments are preferably of such size that the compartments A and B will conveniently receive legal cap size papers, and the com-

partments C and D will conveniently receive letter size papers.

The ends of the box have their upper surfaces inclined from their front portions rearwardly and upwardly, as shown in Figure 2, and the back of the box is higher than the front of the box. The compartments B and D have a false bottom 16, which is so arranged that the files or papers in the rear compartments will project above those in the front compartments.

For each of the compartments I provide a series of separator sheets E, comprising separate sheets 17 each preferably being provided with an indicating tab 18 on its upper edge. These tabs 18 may have on them the letters of the alphabet, or any other indexing indices or legends.

The sheets 17 are provided near their lower edges with registering openings 19, and, spaced therefrom, with registering openings 20. I preferably extend a cord 21 through all of the openings 19, and then back through all of the openings 20, and the ends of the cord may be tied into a knot 22. It will be seen that the knot 22 may be so adjusted as to allow more or less slack in the cord, as may be desired.

In the practical use of my improved sorting table or file distributing device, letters, documents and papers of all kinds can be quickly and efficiently filed. All papers to be filed are first placed in a file tray or basket, ready for filing. The papers are thrown in the basket during the day as they come, without any regard to the file in which they are ultimately to be placed. When the time for filing arrives, the letters and papers are taken from this tray or basket and placed on the sorting table (Figure 1) before the operator. The compartment box (Figure 2) is divided into compartments, each compartment corresponding to a file in the office system. The box contains one compartment for each office file, and these compartments are of legal cap size or letter size, depending upon whether the papers to be filed are to be filed in a cap size file or a letter size file.

The separator sheets or guide cards (Figure 3) also correspond to the guide cards in the respective office files, whether alphabetical, numerical, geographical or any other classification. Each compartment of the box is labeled to correspond to the file 110

which it represents in the office filing system.

The operator having before her the letters and papers to be filed, takes the letters or papers from the top of the file in the order in which they come, and distributes them behind the proper guides in the proper compartments of the sorting table. The place where each is distributed, corresponds therefore with the folder or guide in which it will ultimately be filed in the proper office file. After all the letters and papers have been sorted into the proper compartments on the sorting table, the sorting table is rolled to the office files, and the separator sheets or guides are taken from the first compartment corresponding to the first file, and laid on the sorting table at the left side of the operator in the position as shown in Figure 4. The operator then turns down the separator sheets or guides as in Figure 4, turning them the same as the leaves of a book. As the first sheet is turned down any letters or papers in that compartment are filed by the operator pulling out the drawer of the file and placing those letters or papers in the proper place in the file. The operator proceeds turning down the leaves and filing the papers straight on through the file in the order in which they come. When this file is completed, the separator sheets are returned to the compartment, and the separator sheets taken from another compartment and the papers therein filed in another file in the same way. This operation is continued until the filing is complete.

By this method, and with the aid of this novel and improved device, for sorting and distributing the papers to be filed, the routine task of filing is accomplished, expeditiously and efficiently. This method avoids going back and forth through the office files, pulling out drawers again and again and criss-crossing back and forth with consequent loss of time and energy, as is the case under the ordinary method of filing. By this device, all papers to be filed in one place are brought together so that they are all filed with one operation at one time. This device is adaptable to any filing system

whether for just ordinary correspondence filed alphabetically, or a large filing system containing many different files or departments. By the use of this improved and novel device, the sorting of the letters or papers is rendered simple, accurate and speedy; and when once sorted, the filing goes progressively, straight through the files, without confusion, delay or wasteful hunting for the proper file.

The use of this device eliminates mistakes, waste motions and unnecessary time and enables the operation of filing to be reduced to a standard operation, repeated daily or periodically in the same way and in the same method with the same appliances, thus promoting standard efficiency and routine speed and accuracy.

This device is designed and constructed to enable the principles of efficiency to be applied to the routine work of filing and by its convenience, simplicity and novel use of improved appliances it eliminates waste time and energy and contributes materially to the solving of the practical problems of office filing.

Some changes may be made in the construction and arrangement of my improved device without departing from the real spirit and purpose of my invention, and it is my intention to cover by my claim any modified forms of structure or use of mechanical equivalents which may be reasonably included within its scope.

I claim as my invention:

In a sorting device of the class described, a container having a plurality of rear compartments of different sizes as to width, a plurality of similar forward compartments, a group of separator sheets for each compartment, each group being freely removable from its compartment, a flexible member extended through each group of sheets in the form of a loop, whereby the sheets of each group are freely slidable upon two stretches of each flexible member, each rearward compartment having a higher bottom than each forward compartment.

Des Moines, Iowa, February 16, 1920,
DWIGHT G. McCARTY.
